CLAIM

The ornamental design for a sleeve for a liquid container, as shown and described.

DESCRIPTION

FIG. 1 is a perspective view of a liquid container shown in phantom having a first embodiment of a sleeve for a liquid container in accordance with the design placed there around;

FIG. 2 is a front perspective view of the first embodiment of the sleeve for a liquid container in an unfolded configuration in accordance with the design;

FIG. 3 is a rear perspective view of the first embodiment thereof shown in FIG. 2;

FIG. 4 is a front view the first embodiment thereof shown in FIG. 2;

FIG. 5 is a rear view the first embodiment thereof shown in FIG. 2;

FIG. 6 is a left side view the first embodiment thereof shown in FIG. 2;

FIG. 7 is a right side view the first embodiment thereof shown in FIG. 2;

FIG. 8 is top view the first embodiment thereof shown in FIG. 2;

FIG. 9 is a bottom view the first embodiment thereof shown in FIG. 2;

FIG. 10 is perspective view the first embodiment shown in FIG. 2 illustrating exemplary surface designs which may be utilized for particular social or holiday seasons;

FIG. 11 is a perspective view of the sleeve for a liquid container of FIG. 2 in a folded and collapsed configuration which may be utilized for storage, shipping, and the like; FIG. 12 is a perspective view of a liquid container shown in phantom having a second embodiment of a sleeve for a liquid container in accordance with the design placed there around;

FIG. 13 is a front perspective view of the second embodiment of the sleeve for a liquid container in an unfolded configuration in accordance with the design;

FIG. 14 is a rear perspective view of a second embodiment thereof shown in FIG. 13;

FIG. 15 is a front view the second embodiment thereof shown in FIG. 13;

FIG. 16 is a rear view the second embodiment thereof shown in FIG. 13;

FIG. 17 is a left side view the second embodiment thereof shown in FIG. 13;

FIG. 18 is a right side view the second embodiment thereof shown in FIG. 13;

FIG. 19 is top view the second embodiment thereof shown in FIG. 13;

FIG. 20 is a bottom view the second embodiment thereof shown in FIG. 13;

FIG. 21 is perspective view the second embodiment shown in FIG. 13 illustrating exemplary surface designs which may be utilized for particular social or holiday seasons; and,

(Continued)

FIG. 22 is a perspective view of the sleeve for a liquid container of FIG. 13 in a folded and collapsed configuration which may be utilized for storage, shipping, and the like. Broken lines present in the drawings are for illustrative purposes only and form no part of the design to be patented.
